TENSIONING DEVICE

George L. Leithiser, York, Pa., assignor to General Electric Company, a corporation of New York

Application August 21, 1944, Serial No. 550,365

3 Claims. (Cl. 242—156)

This invention relates to tensioning devices, more particularly to a tensioning device for applying a tension to a filament, and it has for its object an improved device of this character which is smaller and simpler in its construction than tensioning devices heretofore known, and which has improved operating characteristics.

This invention further contemplates a tensioning device which has considerably less weight than those heretofore generally known. This is of great importance since it is the weight of the device which largely determines the speed with which the associated mechanism can be operated. The lighter the weight the faster can the mechanism be operated.

This invention may be used in a variety of applications, such as for tensioning, braiding or wrapping wire that is fed to a cable armoring or braiding machine; tensioning a wire delivered to a coil winding machine, etc.

In carrying out this invention in one form thereof, I provide a bobbin upon which the filament or wire is wound and from which it is drawn to suitable apparatus, such as a cable armoring or braiding machine, particularly to the braiding point. Mounted within the spool are a plurality of plates arranged to be moved into frictional engagement with each other. One of the plates is non-rotatably secured to an axle which supports the spool, but which may be moved longitudinally along the axis of the axle, while the other plate is attached in a similar way to the spool.

A control arm for the plates is located exteriorly of the spool and is arranged to be moved responsive to variations in tension in the filament being drawn from the spool; when the tension attains a predetermined maximum value the arm is moved to release the plates and thereby permit the spool to rotate so that a part of the filament can be payed off. On the other hand, when the tension falls below the desired value the arm is restored and causes the plates to move into frictional engagement to again hold the spool against rotation.

For a more complete understanding of this invention, reference should be had to the accompanying drawings in which Fig. 1 is a side elevation of tensioning apparatus arranged in accordance with this invention; Fig. 2 is a front elevation of the tensioning apparatus shown in Fig. 1; Fig. 3 is a sectional view taken through a portion of the device shown in Figs. 1 and 2; Fig. 4 is a perspective view illustrating various elements of the tensioning device in expanded relation; and Fig. 5 is a perspective view illustrating certain ele-

ments of the tensioning device, parts being broken away and parts shown in section so as to illustrate certain details of construction.

Referring to the drawings, this invention has been shown in one form as applied to a tensioning device for tensioning wire which is used to armor a cable in a suitable cable armoring machine (not shown). It will be understood, of course, that it can be used for other purposes; thus, it may be used to tension the wire drawn to and used in a coil winding machine to wind a coil with the wire under a predetermined tension.

As shown, the tensioning device comprises a bobbin 10 which has a cylindrical surface 11 upon which the wire 11a (Fig. 1) is wound, and at the ends of which are circular flanges 12.

A suitable axle structure rotatably supports the bobbin 10. As shown more clearly in Figs. 3 and 5, this structure comprises axle members 13 and 14 which are threaded upon the ends of a shaft 15. The member 14 is brazed to the shaft 15 so as to provide a secure one-piece structure. The axle member 13 is secured in proper threaded position by means of a circular lock nut 16. A similar nut 17 at the other end of the shaft 15 is rigidly secured to the member 14.

Rotatably mounted upon the two axle members 13 and 14 is a cylindrical member or sleeve 18 which at its right-hand end is provided with a ball race 19 upon which are seated ball bearings 20—the axle 14 being provided with a complementary seat 21 for the balls. The left-hand end of the sleeve 18 is mounted for rotary motion with reference to the axle 13 through a member 22. As shown, the sleeve 18 and the member 22 have cooperating ball bearing races 23 and 24 respectively in which rotate a plurality of ball bearings 25. The member 22 is provided with a second ball bearing race 26 opposite a race 27 on the axle 13 and upon which races ball bearings 28 are mounted.

The cylindrical member 11 of the bobbin is mounted upon the sleeve 18. This sleeve, as shown, is provided with circular flanges 29 and 30 at its opposite ends, and upon which the cylinder 11 is mounted. Secured to the surface of the sleeve 18 between the flanges 29 and 30 is a key 31 which coacts with a suitable keyway (not shown) provided in the inner wall of the cylinder 11 for the purpose of securing the bobbin to the sleeve 18.

The two axle members 13 and 14 are mounted upon a supporting base 32. This base is provided with a pair of spaced-apart upright standards 33 and 34. Secured to these two standards are a

pair of bearing seats 35 and 36 respectively which are open at the top so that the circular nuts 16 and 17 can be moved into them and rotatably supported by the curved bottom walls of the two bearing seats. The bearing members are attached to the standards by means of screws 38a. Attached to the nut 17 is a key 38b fitted to the upright walls of bearing seat 36 so as to prevent rotation of the axle member 14, the shaft 15 and the axle member 13.

Also mounted within the sleeve 18 are suitable means for holding the spool with a predetermined force so that the filament 11a which is withdrawn from the bobbin will be held under a predetermined tension. For this purpose, there are provided a plurality of spaced friction plates 37, which are non-rotatably mounted upon the right-hand axle member 14, the part of the axle upon which these plates are mounted having a non-circular cross-section, as shown in Fig. 5, and the plates having complementary openings fitted to this axle part. It will be observed that by reason of this arrangement the plates 37 are non-rotatable with reference to the axle 14, but they can move longitudinally with reference to it. Interposed in the spaces between the plates 37 are a plurality of plates 38 which are non-rotatable with reference to the sleeve 18, but which may be moved longitudinally with reference to the sleeve; for the purpose of attaching the plates 38 to the sleeve 18, the sleeve is provided with a plurality of longitudinal keyways 39 spaced circumferentially about its inner wall and which keyways are received by keys provided for them on the plates 38. The two sets of plates 37 and 38 constitute frictional means for applying to the sleeve 18 and hence to the bobbin 10 a predetermined force resisting rotation of the bobbin.

The plates 37 and 38 are held in frictional engagement by means of a nut 41 threaded upon a screw 42 which is formed on an inner extension of the member 22, as shown more clearly in Figs. 3 and 5. The nut 41 has a bore complementary to the non-circular section of the axle member upon which the friction plates 37 are mounted, and thus, while it can move longitudinally, it cannot rotate. Housed within the nut is a compression spring 43 which bears against the inner end of the screw 42 and against an abutment 44 provided on the nut. The nut is made in two sections 45 and 45a for machining purposes, and after machining is assembled and rigidly secured together in any suitable way, as by welding.

The nut 41 and screw 42 have such a long pitch that the pressure of the compression spring 43 tends to move the nut away from the screw and thereby apply pressure to the friction plates 37 and 38 to restrict the movement of the sleeve 18.

The nut 41 is operated through rotation of screw 42 by means of an arm 46 which is rotatably mounted upon the bearing member 36, as shown more clearly in Figs. 4 and 5. Secured to this arm is a plate 47, which plate when the arm is rotated is arranged to engage a plate 48 which is an integral part of the screw member 22; as shown, the plate 48 is attached directly to a collar 49 which is threaded upon and integrally united with the screw member 22. When the arm 46 is rotated clockwise, as viewed in Figs. 1, 4 and 5, the end surface 50 of the plate 47 engages the end surface 51 of the plate 48 so as to rotate the nut member 22 clockwise. This rotation of the nut member withdraws the nut 41 against the pressure of the spring 43 and thereby

releases the friction plates 37 and 38 so that the sleeve 18 is released to permit the bobbin 10 to rotate. On the other hand, when the arm 46 is rotated counter-clockwise, the pressure of the spring 43 acting upon nut 41 forces the nut 41 inwardly against the plates to force them into engagement and thereby again hold the bobbin 10 from rotating with a predetermined force.

The arm 46 is rotated responsively to the tension in the filament 11a drawn from the bobbin. For this purpose, the arm rotatably supports one end of a spool 54, the other end of which is similarly supported in an arm 55 which is similar to the arm 46, but which is rotatable upon the bearing member 36 of standard 34. The two arms are biased in the counter-clockwise direction, as viewed in Figs. 1 and 4, by means of helical springs 56. Each spring has one end anchored to the arm 46, 55, and the other end anchored to upright members 33 and 34 through slotted studs 57 which are secured to upright members 33 and 34 by welding.

In the operation of the machine, it will be understood that the filament 11a from the bobbin 10 passes under the roller 54 and thence upwardly to the apparatus which is using the wire, the apparatus drawing the wire from the bobbin. The bobbin is held stationary by the friction plates 37 and 38 when the arm 46 is in its position shown in Figs. 1 and 4, but as the tension in the filament is increased by the apparatus drawing it upwardly, the attached arms 46 and 55 are rotated clockwise, and when the arm 46 attains substantially the dotted line position shown in Fig. 1, its plate 47 engages the plate 48 to turn the screw 42 to move the nut 41 outwardly to release the friction plates. This frees the bobbin 10 to rotate, and a length of the filament is drawn from it. When the tension in the filament again reduces, the arm 46 moves back to its original position under the bias of the springs 48, and the spring 43 is released to move the nut 41 inwardly to again force the friction plates into engagement with predetermined force. In this way, successive lengths of the filament 11a are drawn from the bobbin, but the length of the filament extending from the tensioning device to the apparatus utilizing the filament is held under a substantially constant tension.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to secure by Letters Patent of the United States is:

1. A tensioning device for a filament comprising a bobbin having a wall defining a spool surface upon which the filament is wound and from which it is drawn, axle means rotatably supporting said bobbin, members within said bobbin housed by said wall constructed and arranged to be forced into frictional engagement, one member being nonrotatably attached to said wall but movable longitudinally relative to it and another being attached in a similar way to said axle means, means forcing said members into frictional engagement so as to resist rotation of said bobbin with a predetermined force, and means operated responsively to a predetermined high tension in said filament that is drawn from said bobbin for controlling the operation of said last-named means so as to release said members and

thereby permit said bobbin to rotate, and for causing the reengagement of said members to stop the bobbin when said tension falls below said predetermined value.

2. A tensioning device for a filament comprising a bobbin having a cylindrical wall forming a spool surface upon which the filament is wound and from which it is drawn, an axle extending through said wall supporting it for rotation, a pair of plates within said wall surrounding said axle—one non-rotatably attached to said axle, but mounted for longitudinal movement with reference to it, and the other attached in a similar way to said wall, means holding said plates in frictional engagement to resist rotation of said bobbin with a predetermined force, an arm movably mounted with reference to said bobbin, said arm having a part over which the filament drawn from said bobbin is directed so that the arm is moved by increasing tension in the filament, and connection means between said arm and said plate holding means for operating said means to release said plate and thereby free said bobbin when said arm is moved a predetermined extent.

3. A tensioning device for a filament comprising a bobbin having a cylindrical wall forming

a spool surface upon which the filament is wound and from which it is drawn, an axle extending through said wall supporting it for rotation, a plurality of plates within said wall around said axle, alternate ones of said plates being non-rotatably secured to said axle but free to move longitudinally with reference to it, and the others being similarly attached to said wall, a nut within said wall, a screw within said wall upon which said nut is threaded, said screw forcing said nut to hold said plates in frictional engagement to thereby resist rotation of said bobbin with a predetermined force, an extension arm rotatable in the axis of rotation of said bobbin, a member on said arm over which the filament fed from said bobbin passes so that the tension in the filament tends to rotate the arm in a predetermined direction, a spring resisting the rotation of said arm in said direction and said arm and screw having plates which interengage when said arm is moved by increased tension in said filament in said direction through a predetermined arc and upon further movement of said arm in said direction said plates turn said screw to operate said nut to release said plates and thereby said bobbin.

GEORGE L. LEITHISER.
